TRANSPORTABLE REFRIGERATION UNIT

Charles R. Beltz, 500 Lakeland Ave., Grosse
Pointe, Mich.

Filed July 13, 1959, Ser. No. 56,750

Term of patent 14 years

(Cl. D67—2)

FIG. 1 is a side perspective view of a transportable refrigeration unit showing my new design;

FIG. 2 is an elevational view showing the opposite side thereof;

FIG. 3 is a side perspective view of a modified form of the transportable refrigeration unit shown in FIGS. 1 and 2.

I claim:

The ornamental design for a transportable refrigeration unit, substantially as shown and described.
